SUNBURN PREVENTIVE

John Miglarese, Cincinnati, Ohio, assignor to The National Marking Machine Company, Cincinnati, Ohio, a corporation of Ohio

No Drawing. Application June 23, 1941,
Serial No. 399,401

4 Claims. (Cl. 167—90)

There are on the market several sunburn preventives, generally called "sun tan" lotions, which contain an ingredient having the characteristic of absorbing the shorter wave lengths of the solar rays generally described as ultraviolet rays or rays having a wave length of from 3000 to 3600 Angstrom units and converting them to wave lengths greater than 4000 Angstrom units which will not burn or injuriously affect the human skin and which will not decolorize human hair. Said ingredient, which may be termed the vitalizing ingredient, is usually carried in a vehicle of greasy nature, such, for illustration, as petroleum jelly, and this is applied to the portions of the human skin and hair which it is desired to protect. With such sun tan lotions the vitalizing ingredient is readily and easily washed or rubbed off with the vehicle, and when the vehicle is thus removed all protection against sunburn goes with it. Furthermore, with such sun tan lotions the lotion must be applied to the skin in a relatively thick layer which is clearly visible and, therefore, objectionably unsightly.

My object is to provide a sunburn preventive in which the vitalizing ingredient has an affinity for human skin and hair and which, when carried in a suitable vehicle and applied to the skin and hair will adhere to the skin and hair after the vehicle has been removed, in a manner similar to that of a basic dyestuff applied to silk or wool, and which cannot be washed or rubbed off, and, therefore, will protect the user from the injurious effects of direct sunlight for a relatively long time.

A further object is to provide a sunburn preventive which is substantially colorless and which, when applied to human skin and hair, and after the vehicle has been removed, will be in such a thin layer and colorless to such a degree that it is not clearly visible or of such greasy nature as to detract from the appearance of the user.

My improved vitalizing element has five important characteristics:

1. It is highly fluorescent in ultraviolet light or light rays of wave lengths from 3000 to 3600 Angstrom units. This indicates a high absorption in this region;
2. It is light in color and, therefore, substantially invisible when placed on the human skin or hair;
3. It is soluble, or compatible with neutral non-irritating vehicles;
4. It is not toxic and will not irritate normal skin or hair;
5. When it is carried in a vehicle and applied to human skin or hair, its vitalizing ingredient has an affinity for human skin and hair, that is, is substantive to human skin and hair, independent of any adherence of the vehicle, whereby the said ingredient renders the outer surfaces of the

skin and hair opaque to ultraviolet light even after removal of the vehicle.

My vitalizing ingredients may be described chemically as heterocyclic, aromatic, light colored, fluorescent, basic compounds.

It is recognized that there are two essential parts of a fluorescent molecule; first the "luminophore," which in this case is the heterocyclic and aromatic rings; and second the "fluorophore," which in this case is a basic auxochromic group. It is known that it is not necessary to have either a heterocyclic ring, or a basic auxochrome in order to have fluorescence, for it is possible to have an aromatic ring for the luminophore, and certain other unsaturated groups, such as another aromatic ring, for the auxochrome.

I have obtained satisfactory results with the following formulae for the vitalizing ingredient. The numbering of positions is in accord with Chemical Abstracts, vol. 31 on.

9-ethyl 3-dimethylamino carbazole

This compound is brilliantly fluorescent, due to the dimethylamino group. 5-ethyl carbazole is itself faintly fluorescent. In this case one of the aromatic rings acts as the auxochrome. In addition to promoting fluorescence, the dimethylamino group gives the molecule an affinity for human skin and hair.

4-methyl 7-diethylamino coumarine

The coumarine nucleus is the luminophore and the diethylamino group is the auxochrome promoting fluorescence and causing affinity for skin and hair.

50 3-methyl 5-dimethylamino azimidobenzene

The methyl-azimidobenzene nucleus is the luminophore, the dimethylamino group is the auxochrome promoting fluorescence and giving an affinity for skin and hair.

2-(*para* amino phenyl) 5-amino benzimidazoleHere there are actually three auxochromes, the 2-phenyl, the para amino and the 5-amino groups. The phenyl group promotes only weak fluorescence, but the para-amino and 5-amino groups give a much stronger fluorescence and give an affinity for skin and hair.

2-phenyl 5-amino benzoxazole

The benzoxazole ring is the luminophore. Here there are two auxochromes, the 2-phenyl, which gives weak fluorescence, and the 5-amino, which gives strong fluorescence and gives the molecule an affinity for the skin and hair.

2-(*para* amino phenyl) 6-methyl benzthiazole
(commonly called dehydrothioc-*para*-toluidine)The benzthiazole is the luminophore. Here there are two auxochromes, the 2-phenyl and the para-amino groups. The phenyl gives only a weak fluorescence, the para-amino gives a much stronger fluorescence and gives the compound an affinity for skin and hair.

3-dimethylamino acridine

Here the luminophore is the pyridine and unsubstituted benzene ring. The other benzene ring and dimethylamino group are the auxochromes. The benzene ring gives only a faint fluorescence, the dimethylamino group gives a strong fluorescence and in addition gives the molecule an affinity for skin and hair.

It is to be noted that each of the above mentioned compounds includes an amino or a substituted amino group, and that appears to be a characteristic which is essential to render a fluorescent dyestuff useful in my present invention.

The first three desired properties, namely fluorescence under ultraviolet light of wave length 3000 to 3600 Angstrom units, substantial lack of color, and solubility in suitable solvents, may be rapidly and easily checked. The fourth, non-toxicity to human skin, requires the usual biological methods of testing. The fifth, affinity for the human skin and hair, may be examined by testing the affinity the compound has for protein fibers, namely silk and wool. Merely immerse the piece of silk or wool in an aqueous or alcoholic solution of the compound and wash and rinse thoroughly in warm water. Then examine the piece of silk or wool under an ultraviolet light, such as the General Electric H-4 Black Bulb, in the substantial absence of visible light. A strong fluorescence shows the compound has an affinity for these protein fibers and has

an affinity for human skin and hair. The affinity for skin and hair is not as great as is the affinity for silk and wool, probably because the skin is living matter. In the specification and claims

5 I have referred to this characteristic of affinity for human skin and hair by the expression "substantive to human skin and hair." By that, I mean that the fluorescent compound, although colorless, reacts with or is absorbed in human 10 skin and hair, without the use of any mordant, after the manner of a substantive dye.

My compounds are all definite chemical compounds with definite solubilities and other properties. These compounds are intrinsically fluo-

15 rescent and therefore do not require the addition of extraneous substances, such as acids or bases, to promote fluorescence. For example the naphthol sulfonic acids will not fluoresce in a medium of pH less than 9, and quinine sulfate will not 20 fluoresce in a medium of pH more than 5. Both of these extreme values would irritate tender skin.

My compounds may be applied, either in the form of a solution, such as a mixture of ethanol, water and glycerol; dissolved or dispersed into 25 a paste with such vehicles as vanishing cream or "Carbowax"; or merely diluted with some inert powder, such as talcum powder or zinc stearate, and dusted on the skin and hair.

In whatever manner the essential ingredients 30 be carried, the method of application is the same. The composition is rubbed on the skin or hair and allowed to remain on for at least five minutes. The fluorescent compound affixes itself to the skin or hair in much the same manner that 35 a colored dyestuff affixes itself to textile fibers from a dye bath. The vehicle is then washed or rubbed off. The amount that remains on affixed to the skin or hair is sufficient to give protection against harmful ultraviolet rays for a period of 40 twenty-four hours.

My preferred compositions of matter are as follows:

- A. Into 100 mls. of a mixture of 70 parts ethanol, 25 parts water, and 5 parts glycerol by volume, 45 dissolve 3 grams of any one of the said vitalizing ingredients;
- B. Into 100 grams of vanishing cream, thoroughly grind or incorporate 3 grams of any one of the said vitalizing ingredients;
- C. Into 100 grams of "Carbowax," a water soluble synthetic wax obtainable from Carbide and Carbon Chemical Corporation, thoroughly grind or incorporate 3 grams of any one of the said vitalizing ingredients.
- D. Into 100 grams of talcum powder, or zinc stearate, thoroughly incorporate 5 grams of any one of the said vitalizing ingredients.

In practice I have dissolved or dispersed, or ground into or incorporated into the various vehicles mentioned, a small quantity of the various vitalizing ingredients mentioned, and forming a paste. I have rubbed this on the skin and hair to be protected, and permitted it to remain in such condition for about five minutes; during 60 that time I have found that a sufficient quantity of the vitalizing ingredient has, by reason of its affinity to the skin and hair, become affixed thereto. I have then washed or rubbed substantially all of the vehicle from the skin and hair. The remaining vitalizing element on the skin and hair was in such a thin layer and being substantially colorless was not objectionably visible and did not detract from the appearance of the 70 person to which it was applied. I have demon-

strated that with persons more than usually susceptible to sunburn, and when exposing portions of the skin generally covered by clothing to sun rays for long periods of time, that the skin was mildly tanned but not sunburned and that the hair was not decolorized.

I have also demonstrated that although my vitalizing ingredient becomes affixed to human skin and hair somewhat in the manner of basic dyestuffs' adherence to silk or wool, that it will remain on the skin and hair only for a period of about 24 hours, after which it is removable by bathing or rubbing, or in some manner it disappears. This is probably due to the fact that the living tissues to which it is applied function to remove it. A fresh application of my sunburn preventive was applied each day for several days of exposure, and finally the sun tan became sufficiently intense to substantially protect the person from sunburn.

My improved method of applying sunburn preventive to the human skin and hair is as follows:

The vitalizing ingredient is dispersed in a vehicle of a non-greasy character and readily removable, or in a powder such as ordinary face powder which will adhere to the skin and hair. This is applied to the skin and hair in the ordinary manner and permitted to remain for a short time. I have had satisfactory results by permitting it to remain for five minutes. During that time a sufficient amount of the vitalizing ingredient for sunburn prevention separates from the vehicle and adheres to the skin and hair, due to its affinity for the skin and hair. Then the vehicle and other ingredients contained therein are washed or rubbed off, with the result that only a microscopic layer of the vitalizing ingredient remains, and since that is substantially colorless, it is not objectionably visible and does not detract from the appearance of the user.

I claim as my invention:

1. A sunburn preventive to be applied as a coating to human skin and hair for the purpose of rendering the outer surfaces thereof, after removal of the coating, opaque to ultraviolet light comprising a non-toxic carrier having dispersed therein a colorless, fluorescent, basic compound, substantive to human skin and hair, selected from the group consisting of

9-ethyl 3-dimethylamino carbazole

4-methyl 7-diethylamino coumarine

3-methyl 5-dimethylamino azimidobenzene

2-(para amino phenyl) 5-amino benzimidazole

2-phenyl 5-amino benzoxazole

2-(para amino phenyl) 6-methyl benzthiazole

3-dimethylamino acridine

2. A sunburn preventive to be applied as a coating to human skin and hair for the purpose of rendering the outer surfaces thereof opaque to ultraviolet light, after removal of the coating, comprising a suitable carrier having dispersed therein the compound, 9-ethyl 3-dimethylamino carbazole, having the following structural formula:

3. A sunburn preventive to be applied as a coating to human skin and hair for the purpose of rendering the outer surfaces thereof opaque to ultraviolet light, after removal of the coating, comprising a suitable carrier having dispersed therein the compound, 4-methyl 7-diethylamino coumarine, having the following structural formula:

4. A sunburn preventive to be applied as a coating to human skin and hair for the purpose of rendering the outer surfaces thereof opaque to ultraviolet light, after removal of the coating, comprising a suitable carrier having dispersed therein the compound, 3-methyl 5-dimethylamino azimidobenzene, having the following structural formula:
